UNITED STATES PATENT OFFICE.

FREDERICK J. NEWMAN, OF CHICAGO, ILLINOIS.

WINDOW-FRAME FOR FLEXIBLE CURTAINS.

No. 856,542.

Specification of Letters Patent.

Patented June 11, 1907.

Application filed December 15, 1906. Serial No. 348,013.

To all whom it may concern:

Be it known that I, FREDERICK J. NEWMAN, a citizen of the United States, residing at Chicago, in the county of Cook and State 5 of Illinois, have invented certain new and useful Improvements in Window-Frames for Flexible Curtains, of which the following is a specification.

My invention pertains to a frame adapted 10 to be secured to a flexible support, and is especially fitted for a window frame in the sides or curtains of a foldable top for vehicles, where it is desired that the top shall fold compactly, and present a neat and finished exterior 15 and internal appearance.

The window frame is best illustrated as applied to the sides of a foldable top, and a brief description of some of the known methods of attaching this type of frame will best illustrate the advantages of applicant's device over the present constructions.

A common method is to rigidly secure a frame to one of the bows or ribs in a foldable top and consequently the top is prevented 25 from folding compactly which results in the driver or operator of the vehicle being unable to see behind over the folded top thereon. Other disadvantages are in the facts that where two parts of a frame are secured together 30 it wrinkles the flexible support around the edges of the frame, as well as draws the support inward in such a manner that the ribs or bows become prominent from the outside of the vehicle due to the fact that a flexible support, such as a vehicle top, is generally 35 composed of two parts, namely—the outside leather and the inside lining with a margin between for the ribs or bows.

In my construction I have provided a 40 frame that may be firmly attached to a flexible support without the aid of the bow or rib to secure it thereto, and, furthermore, the parts of my frame are secured together so that the flexible support is in no wise injured 45 or wrinkled, nor are the bows in a foldable top made prominent which is due to the filling piece or intermediate frame member used in my construction.

Other advantages are in its simplicity and 50 durability as well as its adaptability to flexible supports, the distance between the two parts of which varies.

In the accompanying drawing Figure 1 is a front elevation of my device with the parts

shown in section; and Fig. 2 is a cross-sectional edge view on the line 2—2 of Fig. 1.

Referring now more particularly to the drawing, 4 and 5 constitute the two side frames of the frame as a whole, which are preferably composed of metal, such as brass, 60 and in this particular instance are circular in form. The side frame 4 is provided with a flat surface 6 on one of its sides and the threaded apertures 7, while the side frame 5 has an annular flange 8 on its inner face and 65 the apertures 9 through which the shank of the screws 10 pass and are adapted to be screwed in the threaded aperture 7. Interposed between the two side frames is the intermediate frame or filling member 11 which, 70 in this instance, consists of an annular wooden ring the outside diameter of which is preferably larger than the outside diameter of the two side frames, so as not to present a metallic edge to the flexible support, and is provided 75 on its inner edge on one side with a slightly countersunk portion, as shown at 12, in which a transparent material such as glass 13 is seated and held therein by means of the side frame 4. Apertures 14 are provided in 80 the intermediate member through which the screws 10 are adapted to pass.

In Fig. 1, 15 represents as a whole a flexible support or a curtain of a vehicle, which is generally composed of two parts 16 and 17, 85 the part 16, being the external portion and exposed to climatic changes, is preferably composed of a water proof or hard material, such as leather, while the part 17 consists of cloth, canvas or the like. To attach my 90 frame to the flexible support the part 16 is preferably provided with an aperture of substantially the same diameter as the distance between the inner edges of the side frame 4, while the part 17 is provided with an aperture 95 of less diameter than the distance between the inner edges of the side frame 5, so that when the side frame 5 is pressed against the intermediate member the part 17 of the curtain being interposed between the two 100 members [the apertures therein registering with the side frames and intermediate member] a portion of the fabric, as shown at 18, is clamped against the intermediate member by the flange 8. The transparent material 105 or glass 13 is then seated in the countersunk portion and the side frame 4 held firmly against the intermediate member with the

part 16 therebetween. The screws 10 are then inserted in the registering apertures and the two side frames are drawn against the intermediate member so as to firmly clamp and 5 secure the glass and flexible support.

It is obvious from the foregoing description that there is no twisting movement given to the portion 16 of the curtain so as to wrinkle it in any way, nor is the curtain as a 10 whole drawn in as it otherwise would be if just the two side frames were used without the intermediate filling member.

It is also obvious that the efficiency of my 15 construction would not be impaired greatly if the flange was omitted, but I prefer to construct the side frame 5, as shown, as it aids materially in holding the frame to the flexible support.

It is also obvious that there may be various 20 ways of securing the two frame members to the intermediate member without the use of the means shown, and also that the form of the window frame is wholly immaterial, and therefore without limiting myself to the 25 precise details of construction,

I claim:

1. A window frame adapted to be secured to a flexible support consisting of two separated parts, said frame comprising two side 30 frames and an intermediate member, and means for drawing said frames together whereby the two parts of said flexible support are clamped on opposite sides of said intermediate member, substantially as described.

2. A window frame adapted to be secured to a flexible support consisting of two separated parts, said frame comprising two side frames and an intermediate member, each of 40 said side frames being adapted to hold a transparent and a flexible material against

said intermediate member, on opposite sides thereof, respectively, substantially as described.

3. A window frame adapted to be secured to a flexible support comprising two side frames and an intermediate filling member, a transparent material seated within said intermediate filling member, a flange on one of said side frames, and means for drawing said frames together whereby the transparent material is confined within its seat and the flexible support clamped against, said intermediate filling member, substantially as described. 55

4. A window frame adapted to be secured to a flexible support consisting of two parts separated by a certain distance, said frame comprising two side frames and a filling member of substantially the same thickness as the 60 distance between said two parts, and means for drawing said side frames together whereby a transparent material and the two parts of said support are drawn against said filling member, substantially as described. 65

5. A window frame adapted to be secured to a flexible support consisting of two separated parts, said frame comprising two side frames and an intermediate filling member of substantially the same thickness as the 70 distance between said two parts, each of said side frames being adapted to clamp one of said parts against said filling member, a transparent material confined against said filling member by one of said side frames, 75 and means for clamping said side frames and filling member together, substantially as described.

FREDERICK J. NEWMAN.
